SECURING MEANS FOR ELECTRICAL HIGH VACUUM VESSELS

Gunnar Johan Persson, Ludvika, Sweden, assignor to Allmanna Svenska Elektriska Aktiebolaget, Västerås, Sweden, a Swedish corporation

Application September 26, 1946, Serial No. 699,440
In Sweden September 27, 1945

6 Claims. (Cl. 250—27.5)

1

For obtaining a high-vacuum tight joint between a metal wall and a ceramic body, for instance an electric insulator, it is known to make the metal wall adjacent to the joint of an alloy having a coefficient of thermal expansion which is nearly equal to that of the ceramic body, and to join these two parts by an enamel or glass layer which thus forms the vacuum tight seal between the high-vacuum space and an external space having a higher pressure. There has been considerable difficulties in producing such joints, for instance in the first line the finding of an alloy and a glass quality which do not attack and are not attacked by such vapors as are frequently contained in the high-vacuum space, for instance mercury vapor, and secondly such difficulties which depend on the risk of spoiling or deforming the ceramic body at the high temperatures necessary for the fusion of the glass. These difficulties, which initially caused a very large percentage of rejection of the joints made in the described way, have been surmounted in a very high degree by longer experience. For this reason it has now been found advisable to employ the aforesaid joining method also in such places in high-vacuum, where the glass layer has no sealing function, i. e. where it is surrounded by vacuum on all sides. Such an application of the said method of joining forms the object of the present invention.

The advantage of employing a joint of the aforesaid kind in places surrounded by vacuum on all sides instead of the detachable joint type which has been used before is in the first line that it requires essentially less space than a detachable joint. In most high vacuum vessels, for instance electric valve or so-called gas or vapor discharged vessels, the question of space is very important. It has also been found that by reason of the rigidity of the glass joint it is possible to obtain a very great precision which is of special importance for such parts which are kept under different electric potential in high-vacuum in order to maintain the mutual distances which give a maximum of breakdown voltage.

An application of the invention is shown in the accompanying drawing which shows an insulator bushing for an anode bolt of an ionic valve vessel having two metal parts secured thereto in a longitudinal section in Fig. 1 and in a cross section in Fig. 2, a vessel 11 being shown in section at Fig. 3 surrounding the insulator and the metal parts thereon, and the end of a tube for evacuating the vessel being shown at 12. Fig. 4 is a detail

2

cross-section showing the joint between the ceramic body and the metallic support.

1 is the insulator bushing made from a ceramic material, for instance porcelain, and which for instance is carried through the metal bottom of the evacuated valve vessel 11 in a vacuum tight manner immediately below the portion shown in Fig. 1. 2 is the anode bolt traversing the insulator and which may be sealed thereto at the lower end 10 of the insulator. The anode bolt is surrounded inside the vacuum vessel 11 and above the insulator by two metal sleeves 3, 4, the inner one 3 for instance carrying a control grid 9 and the outer one 4 the anode sleeve 10, which is open at its lower end. In several cases a larger number of sleeves surrounding the bolt may be present, for instance for carrying several grids or for screening purposes. As all these sleeves and the anode bolt itself frequently are kept at widely different potential values, it is of utmost importance that the distance between the said parts is kept as closely as possible to the value corresponding to a maximum of breakdown voltage. As the sleeves are generally rather long, this necessitates a 25 great precision and rigidity of their supporting parts.

In order to achieve this result the supporting elements, in this form of the present invention, consist of rings 5 and 6 respectively of an appropriate metal alloy, said rings having a conical and a cylindrical portion, which are secured to correspondingly shaped surfaces on the insulator by glass joints. Parts of the cylindrical portions are, however, free from the insulator and serve to secure the sleeves proper 3, 4, which for economical reasons are generally not made from the same material as the rings, but for instance from pure iron, while the rings are made from an alloy, which has about the same coefficient of thermal expansion as the porcelain, for instance composed of iron, nickel and cobalt. Such alloys are available commercially, for instance under the names "sivar" and "kovar." For facilitating a better control of the glass joint between the rings 40 and the porcelain, the former ones are preferably perforated by a circular row of holes 7, through which a portion of the glass mass may penetrate during the fusion as shown in Fig. 4. For facilitating a more precise joint between the rings 45 and the sleeves 3, 4 detachably secured thereto, the said sleeves may be provided with longitudinal slits at their lower end and with weakening circular notches 8, so that the tongues formed between the slits may adapt themselves to the rings. 50 In joining these parts together they are prefera-

bly mounted in a jig, which keeps the parts exactly in the desired mutual position. Also in melting the glass joints the rings and the porcelain are preferably kept in the right mutual position by means of a jig. The joint surfaces on the porcelain are as a rule ground in advance for obtaining the exact shape.

Experience has proved that it will be more easy to place the sleeves 3, 4 in the right position with respect to the porcelain in the now described manner than if secured directly to the porcelain by the detachable joints. Also the joints require less space as compared with the latter type, which is of special importance in ionic valve vessels.

I claim as my invention:

1. A high-evacuated vessel for electrical purposes having a ceramic insulator at least partly inside said vessel and comprising a support wholly enclosed within the vacuum space of said vessel made of a metal alloy having a coefficient of thermal expansion near that of the insulator, a fused glass joint between said support and insulator, and a metal part of a material different from that of said support wholly enclosed within the vacuum space of said vessel and carried by said support.

2. A high-evacuated vessel for electrical purposes having a ceramic insulator at least partly inside said vessel and comprising an annular support wholly enclosed within the vacuum space of said vessel surrounding said insulator and made of a metal alloy having a coefficient of thermal expansion near that of the insulator, a fused glass joint between said support and insulator, and a metal part of a material different from that of said support wholly enclosed within the vacuum space of said vessel and carried by said support.

3. A high-evacuated vessel for electrical purposes having a ceramic insulator at least partly inside said vessel and comprising an annular sheet metal support of angular section wholly enclosed within the vacuum space of said vessel made of a metal alloy having a coefficient of thermal expansion near that of the insulator, a fused glass

5

joint between said support and insulator, and a metal part of a different material from said support wholly enclosed within the vacuum space of said vessel and carried by said support.

10

4. A high-evacuated ionic valve vessel with electrodes therein and having a ceramic insulator traversing the wall thereof, a support wholly enclosed within the vacuum space of said vessel made of a metal alloy having a coefficient of thermal expansion near that of the insulator, a fused glass joint between said support and insulator, and a metal part of a different material from that of said support wholly enclosed within the vacuum space of said vessel and carried by said support.

15

5. A high-evacuated vessel for electrical purposes having a ceramic insulator at least partly inside said vessel and comprising an annular support inside said vessel surrounding said insulator and having a perforated portion closely adhering thereto, said support being made of a metal alloy having a coefficient of thermal expansion near that of the insulator, a fused glass joint between said support and insulator, and a metal part enclosed in said vessel carried by said support.

20

6. A high-evacuated vessel for electrical purposes having a ceramic insulator at least partly inside said vessel and comprising an annular support inside said vessel having a cylindrical portion and made of a metal alloy having a coefficient of thermal expansion near that of the insulator, and enclosed in said vessel a metal sleeve having longitudinal slits at one end which is secured to said support.
